UNITED STATES PATENT OFFICE.

SEBERO JASO, OF SAN ANTONIO, TEXAS.

SAFETY ATTACHMENT FOR RAZORS.

Application filed November 6, 1924. Serial No. 748,041.

To all whom it may concern:

Be it known that I, SEBERO JASO, a citizen of the Republic of Mexico, residing at San Antonio, in the county of Bexar and State 5 of Texas, have invented certain new and useful Improvements in Safety Attachments for Razors, of which the following is a specification.

This invention relates to razors, having 10 more particular reference to a safety attachment adapted for application to an ordinary razor, the invention having for an object the provision of a simple and efficient safety attachment of this sort, a further specific object of the invention relating 15 to the provision of means of adjusting the attachment to suit blades of varying width.

For further comprehension of the invention, and of the objects and advantages thereof, reference will be had to the following description and accompanying drawing, and to the appended claims in which the various novel features of the invention 25 are more particularly set forth.

Fig. 1 of the drawing is a side view of a razor having my improved attachment applied thereto.

Fig. 2 is an enlarged transverse sectional view taken on the line 2—2 of Fig. 1.

Fig. 3 is a fragmentary longitudinal sectional view taken on the line 3—3 of Fig. 2.

Fig. 4 is a face view, showing the opposite face to that shown in Fig. 1.

In the drawing the reference numeral 10 indicates the blade of an ordinary razor, and 11 the handle to which the blade is hinged. My improved device comprises a channeled strip 12 that is adapted to be 15 slipped over the back of the blade, fitting snugly against the latter, the legs 12' and 12^a of this strip being of less height than the width of the blade, the legs 12^a supporting the adjustable guard element. This adjustable guard element comprises an elongated plate 15 that is formed on one edge with serrations 16, this serrated edge projecting slightly beyond the cutting edge of the blade 10 as indicated. Formed on the leg 12^a of the member 12 is a channeled rib 18 that is spaced a slight distance from the web portion of said member, and which may be conveniently formed by doubling the sheet material of which the member is formed 20 upon itself. The rear edge of the plate 15 is normally spaced slightly in front of this

rib 18 and has hinged thereto as at 19 a screw 20 that projects through suitable registering apertures 21 in the two walls of the rib, and through a nut 22 positioned 60 in the said rib between the two walls thereof, the nut projecting at one side from the rib, the latter having a slotted aperture 23 therein through which the nut projects.

Formed on the forward edge of the leg 65 12^a of the member 12 is a bracket 25 to which is hinged a screw 26 that extends freely through an aperture 27 in the plate 15, and has a nut 28 threaded in its free end. Fixed each at one end to the said forward edge of the leg 12^a are two flat springs 70 30 which bear at their other ends on the plate 15. The device is applied to the razor by slipping the member 12 lengthwise over the blade, and then tightening the nut 28 75 to cause the serrated edge of the guard 15 to bear against the blade adjacent the cutting edge of the latter. By turning the nut 22 the plate or guard 15 may be moved transversely of the blade, thus accommodating 80 itself to the blade as the latter decreased in width through sharpening.

Having thus described my invention, what I claim as new and desire to protect by Letters Patent of the United States is 85 as follows:

1. A safety attachment for razors, comprising a channeled member adapted to be mounted on the blade of the razor, a guard plate extending across one leg of said member and having an aperture therein, a screw hinged to the rear edge of said guard plate, a nut through which said screw is threaded, said nut being mounted on said member to permit of rotation thereof but 90 prevent axial movement thereof, and means for pressing the front edge of said guard plate against the blade of the razor.

2. A safety attachment for razors comprising a channeled member adapted to be 100 mounted on the blade of the razor, a guard plate extending across one leg of said member and having an aperture therein, a screw hinged to the rear edge of said guard plate, a nut through which said screw is threaded, said nut being mounted on said member to permit of rotation thereof but prevent axial movement thereof, and means for pressing the front edge of said guard plate against the blade of the razor, consisting of a screw hinged to said member 105 and passing through a hole in the said plate,

and a nut threaded on said screw and bearing on said plate.

3. A safety attachment for razors comprising a channeled member adapted for mounting on the blade of the razor, a channeled rib extending along one side of said member, a nut positioned between the walls of said rib, a screw threaded through said nut, a guard plate to which said screw is hinged, a second screw hinged to said member and passing through an aperture in the plate, and a nut threaded on said screw.

4. A safety attachment for razors comprising a channeled member adapted for

mounting on the blade of the razor, a channeled rib extending along one side of said member, a nut positioned between the walls of said rib, a screw threaded through said nut, a guard plate to which said screw is hinged, a second screw hinged to said member and passing through an aperture in the plate, and a nut threaded on said screw, and a pair of springs fixed to said channeled member and bearing on said guard plate to urge the latter away from the blade of the razor. 20 25

In testimony whereof I have affixed my signature.

SEBERO JASO.
